US00D410650S

United States Patent [19]

Hara

[11] Patent Number: Des. 410,650

[45] Date of Patent: ** Jun. 8, 1999

[54] **DIGITAL AUDIO DISK PLAYER WITH CAR TUNER**D. 372,915 8/1996 Ito et al. D14/188
5,177,730 1/1993 Utsugi .... 369/75.1[75] Inventor: **Akira Hara**, Tokyo, Japan

Primary Examiner—Ted Shooman

Assistant Examiner—Nanda Bondade

Attorney, Agent, or Firm—Jacobson, Price, Holman & Stern, PLLC

[**] Term: **14 Years**[57] **CLAIM**[21] Appl. No.: **29/088,950**

The ornamental design for a digital audio disk player with car tuner, as shown and described.

[22] Filed: **Jun. 4, 1998****DESCRIPTION**[30] **Foreign Application Priority Data**

Jan. 7, 1998 [JP] Japan 10-101

FIG. 1 is a perspective view of my new design;

[51] **LOC (6) Cl.** **14-01**

FIG. 2 is a front elevational view thereof;

[52] **U.S. Cl.** **D14/168; D14/156; D14/188**

FIG. 3 is a rear elevational view thereof;

[58] **Field of Search** D14/124, 137,

FIG. 4 is a top plan view thereof;

D14/157, 158, 168, 188, 197-198, 257-258,
265, 299; 455/73, 89-90, 128, 345-347;

FIG. 5 is a bottom plan view thereof;

369/75.1, 75.2, 77.1, 77.2

FIG. 6 is a left elevational plan view thereof;

[56] **References Cited**

FIG. 7 is a right elevational plan view thereof;

U.S. PATENT DOCUMENTS

FIG. 8 is a front view showing movable parts; and,

D. 252,027 6/1979 Imazeki D14/198

FIG. 9 is a left side view showing movable parts.

D. 351,167 10/1994 Yun ..... D14/157 X

The undisclosed views of the movable parts of the digital

D. 356,316 3/1995 Culbertson D14/257

audio disc player with car tuner form no part of the claimed

design.
